United States Patent Office

Des. 213,034
Patented Dec. 31, 1968

213,034

SNACK FOOD PRODUCT OR THE LIKE

Lyle Slaybaugh, Battle Creek, Mich., assignor to Kellogg Company, Battle Creek, Mich., a corporation of Delaware

Filed Oct. 25, 1967, Ser. No. 9,157

Term of patent 14 years

(Cl. D1—2)

FIG. 1 is a front elevational view of a snack food product showing my new design, the back thereof being a substantial mirror image, and

FIG. 2 is a side elevational view thereof.

FIG. 3 is a top plan view, and

FIG. 4 is a bottom view thereof.

I claim:

The ornamental design for a snack food product or the like, substantially as shown and described.
